JOHN B. MACARTHUR, OF WEST LYNN, AND ROBERT C. SANSON, OF EAST MILTON, MASSACHUSETTS, ASSIGNORS TO ANDREW DUTTON COMPANY, OF BOSTON, MASSACHUSETTS, A CORPORATION OF MASSACHUSETTS

CURTAIN-ROLL CRADLE

Application filed December 30, 1927. Serial No. 243,581.

This invention relates to curtains and fixtures therefor adapted for the stage or for dividing a large room into small rooms, or similar uses, and aims particularly to provide a novel cradle for supporting the roller and curtain intermediate its ends.

In the drawings illustrating one form of our invention described herein,

Fig. 1 is a side elevation, partly broken away, of a curtain roller and its supports, and means for rotating the roller;

Fig. 2, a vertical section on the line 2—2, Fig. 1, showing the curtain partly unrolled;

Fig. 3, a plan of the cradle; and

Fig. 4, a similar view to Fig. 2 with the curtain substantially rolled up.

Our novel cradle, Fig. 2, comprises one or more, herein two, pairs of jaws 1, 1, of any convenient, conventional form adapted to grip the opposite edges 2 of an I-beam 3 or the like, such as is commonly used in building construction.

These jaws may be drawn toward and against the beam by a rod 4 passing through the jaws and secured by a nut. Two pairs of these jaws, each pair comprising a front and a rear jaw, Fig. 1, are used with each cradle and depending from each pair of jaws, Fig. 3, is a plate 6 secured thereto by bolts 7 and this plate is provided with a central longitudinal slot 8 in which are secured, as by bolts 9, a depending front roller bracket 10 and a curved depending rear roller bracket 11.

Cradles for use with awning rollers have been commonly used where the awnings for windows and doors are movable laterally, as over the sidewalk. But this type of cradle is not usable with a vertically moving curtain. In the latter case the curtain must be free to unroll and roll without the unrolled portion coming into contact after it leaves the curtain roller with any other roller to such an extent as will permit the curtain by any possibility, to be swerved out of its path by and partly rolled or unrolled upon said roller.

To avoid this difficulty, Figs. 2, 4, we provide the bracket 11 with a supporting roller 12 and at each side or front and back thereof,

and a little higher we provide a guard roller 13, 14, each of any convenient length. The curtain roller 15 rests upon and is mainly carried by the supporting roller 12. The brackets 10, 11, are, of course, adjusted relative to each other to accommodate the roller 15, whatever its diameter, and its curtain 16, so that when the curtain is rolled up it will substantially fill the space between the rollers 13, 14 and rotate easily between them.

The foregoing arrangement provides a clear substantially vertical passage between the supporting roller and the nearest guiding roller for the movement of the curtain. Obviously, the nearer the rolling and unrolling curtain moves vertically, the less the friction created by its travel as it rubs against the supporting and guiding rollers with consequent less wear of the curtain and tendency to create wrinkles therein.

Consequently, structures comprising two or more curtain roller supporting rollers which jointly support the curtain roller are impractical, because of the strain on the curtain material necessitated in moving it over the supporting rollers.

By our novel construction, we avoid the danger pointed out in the preceding paragraph and provide means whereby the curtain may safely and certainly be rolled and unrolled smoothly without the difficulties experienced in the use of other constructions which have been tried and found impracticable.

When the curtain is being rolled up or raised, the motion of the roller 15 together with the additional weight of the curtain 16 will cause it to move slightly to the, Fig. 4, right of the center of the supporting roll 12 and against guide roll 14.

When the curtain is being unrolled or lowered, the motion of the roller 15 in the opposite direction with the added weight of the curtain on the side toward which the roller is turning will cause the roller to move to the, Fig. 2, left against the guide roller 13. In both cases it will be noted that the curtain 16 will have a clear passage in which to ascend or descend. An additional guiding roll 17 is shown and may be used, if desired, to

assist in smoothing out any folds or wrinkles in the curtain before it reaches the roll 15 on its upward travel.

Curtain rollers 65 or more feet in length may be installed readily with the aid of my novel cradle and used without difficulty. In such cases a cradle is preferably placed at about every twenty feet throughout the length of the roller.

10 At one end of the roller 15 is shown, Fig. 1, a convenient and conventional form of actuating it, as a gear in a box 18, on a shaft 19, in mesh with a gear, not shown; on the roller end, with a universal joint 20, and a set of gears in a box 21, the whole controlled by a handle 22, the gear boxes 18, 21, being secured to the wall adjacent the proscenium arch or other opening the curtain is designed to close. Two of these actuating devices are frequently used, one at each end of the roller.

A curtain and its roller frequently weighs 500 pounds or more, and of course settles or sags somewhat in the center, but with my novel cradle support, it may be readily rolled 25 and unrolled smoothly and without difficulty.

This invention is not limited to the precise embodiment thereof described and illustrated herein, but is more particularly pointed out in the following claims.

30. Claims:

1. A curtain roller cradle comprising a support engaging top plate, front and rear roller carrying arms depending thereon with rollers spaced to provide a substantially vertical passage therebetween for the curtain.

2. A curtain roller cradle comprising a ceiling engaging top plate, front and rear roller carrying arms thereon with rollers, a plurality of the latter positioned vertically 40 and a plurality of them positioned in a curved line to provide a centrally positioned supporting roller and a guard roller in front and at the rear thereof.

3. A curtain roller cradle comprising a top plate, roller carrying arms thereon with rollers in U-shaped formation thereon with an upright passage between three of them for the curtain.

4. A curtain roller cradle comprising a top plate, a straight and a curved roller arm thereon spaced apart vertically and carrying a roller on each arm.

5. A curtain roller cradle having a plurality of roller supporting arms, one straight and one curved, providing a vertical curtain space between them equal at least to the thickness of the curtain, with a roller on one arm supporting the curtain roller substantially centrally thereover during unrolling of the curtain, and a guide for the curtain at either side of the supporting roller.

In testimony whereof, we have signed our names to this specification,

JOHN B. MACARTHUR.
ROBERT C. SANSOM.
